UNITED STATES PATENT OFFICE

111,523

DESIGN FOR A WASHING MACHINE

Edward S. Preston, Hinsdale, Ill., assignor to Chicago Electric Manufacturing Company, Chicago, Ill., a corporation of Illinois

Application August 1, 1938, Serial No. 79,010

Term of patent 7 years

To all whom it may concern:

Be it known that I, Edward S. Preston, a citizen of the United States, residing at Hinsdale, Du Page County, Illinois, have invented a new, original, and ornamental Design for a Washing Machine, of which the following is a specification, reference being had to the accompanying drawing, forming a part thereof:

Figure 1 is a perspective view of a washing machine showing my new design;

Figure 2 is a fragmentary side elevational view,

as seen from the right or left of Figure 1, of the upper portion of the washing machine; and

Figure 3 is a top plan view of one-half of the washing machine, the opposite half being a duplication of that shown in Figure 3.

The dominating feature of my design resides in the portions illustrated in solid lines.

I claim:

The ornamental design for a washing machine, substantially as shown and described.

EDWARD S. PRESTON.
